METHOD FOR MAKING PAWL OR DETENT MEANS

Floyd D. Wenn, Binghamton, N. Y., assignor to
The Brewer-Titchener Corporation, Cortland,
N. Y., a corporation of New York

Application March 1, 1935, Serial No. 8,930

4 Claims. (Cl. 29—148)

This invention relates to certain novel process steps that facilitate the economical fabrication on a rapid productive scale of a retractable pawl or the like article, such as are commonly utilized in connection with a ratchet wheel or to engage a notched sector of an automobile emergency brake lever; my improvements are also applicable to a wide variety of analogous products of manufacture.

10 In smaller sizes, such pivotally mounted pawls or detent levers are usually stamped up in large quantities from sheet metal stock to form a toe blank. A sharply formed acute angle is needed in the pointed toe region of such spring actuated pawl in order to effectively drop between closely spaced ratchet teeth. As an initial step, a substantially flat pawl blank may be pierced out of relatively heavy sheet metal stock of which the perimeter includes a relatively blunt nose region 15 that is perimetrically shaped to protect the dies against excessive wear and tear in the filleted nose shearing region thereof. The accompanying rather severe stamping blow is found to cause a localized nose region of such blank to become compressed to some extent so as to impart an arcuate deformation to a contiguous side face thereof. Unless a corresponding amount of stock is subsequently restored, such superficial deformation reduces the potential width margin available for a sharpened transverse toe edge when finished in the conventional manner by grinders or equivalent metal working tools.

As an improvement thereon, designed to correct such inherent deficiencies, I preferably resort to a modified coining operation that may be performed in a cold state in order to attain a smoothly sharpened toe edge. Such use of forming dies, not only upsets to restore such initially reduced toe width, but the same operation may be carried out to enlarge the finished toe width beyond the original stock thickness and impress thereon a sharply formed edge without need of any grinding or milling agency. As a result, I am enabled in one operation to economically complete a high grade product of this kind while coining said initial blunt toe and at the same time snipping off a small surplus stock portion to render the sharpened toe free from any jutting tip or other finlike appendage.

50 The object of my invention is to devise an improved processing method of the character indicated and by the use of simple press operations, to shape up a finished pawl or the like article of manufacture from sheet metal stock at a rapid productive rate with the minimum of labor cost.

Reference is had to the accompanying one sheet of drawings which are illustrative of a preferred mode of carrying out my method, and in which:

Fig. 1 represents a fragmental elevational side view of an automotive emergency brake lever assembly having my pawl operatively embodied therein, while Fig. 2 shows a transverse view of Fig. 1.

Fig. 3 outlines the stamped blank contour from which such pawl may be finished; and Fig. 4 is a 10 toe end view thereof.

Figs. 5 and 6 are similar to the last named figures and depict the change in toe contour imparted by a further processing of such blank.

Fig. 7 is illustrative of companion dies by the 15 use of which such pawl may be shaped up to provide for a sharp toe, and Fig. 8 shows a cross-section of such die blank taken along line 8—8 of Fig. 7.

In order to present a more comprehensive understanding regarding the purpose of my pawl devices, it is pointed out that the tubular body of a brake lever may be stamped up from sheet metal to include a hollow shank portion 10 that commonly terminates in bifurcated fork arms 25 such as 11 and 12 adapted to be mounted upon the rotatable fulcrum shaft 13. The swinging end of such lever may be provided with a suitable handle portion and a manipulative grip member (not shown). Such grip serves to actuate the latch rod 14 which may be slidably encased within the tubular lever shank and carried into operative engagement with the latchable pawl 15 in the inverted manner indicated in Fig. 1.

The free fork ends of said lever may have a 35 rivet pin 16 mounted therebetween. The flat sided pawl 15 herein depicted is of the balanced or medially supported lever type including a centrally located pivot aperture arranged to receive said rivet pin. One end of such pawl has a hole 40 21 therethrough into which the latch rod 14 may be hooked, while the opposite pawl end is provided with an acute toe edge 15A that successively interlocks with the closely spaced ratchet teeth 17 of the sector 18. When loosely mounted 45 about the fulcrum shaft, this sector may be retained by a stop pin such as 19. A return spring 20 usually carried by the lever, serves to thrust the pawl toe into operative engagement with said teeth upon release of the lever grip.

The present invention is primarily concerned with the economical fabrication of the pawl element or the like detent means 15. Referring now to Figs. 3 and 4, they show the contour shape of a flat blank 22 as sheared from sheet metal stock 55

and in which the several apertures may be pierced simultaneously therewith. The nose end region of said blank is initially given a relatively blunt nose contour 23. The stock thickness actually used for certain purposes measures around $T_1 = \frac{3}{16}$ ". When such blank is pierced out in one operation in the usual manner, the cutting dies tend to form an arcuate surface deformation as at 24 upon one side face of the blank as indicated in exaggerated scale by Fig. 4 and in which the potential toe length T_2 becomes less than the original stock thickness T_1 . In this same figure, the severed blank edge portion that is finally torn away in shear, is represented by shaded vertical lines designated as 25. The dotted contour 26 indicates the acute shape into which my finished toe is ultimately brought by a special coining operation that will presently be defined. The finished product 27 then assumes a sharpened toe shape corresponding to Figs. 5 and 6, the length of the toe edge T_3 being thereby restored and even increased over the initial stock thickness T_1 . It will be obvious that the preservation of a full toe thickness represents an important requisite in the maintenance of adequate pawl life under severe service conditions. If desired, such acute faces may be subjected to a hardening process.

Figs. 7 and 8 schematically portray a die block element 30 and a cooperating guided punch member 31, which may respectively be provided with oppositely disposed coining jaws such as 32 and 33 respectively having a relatively blunt V-shaped face profile. My blank 22 may be snugly jiggled into a suitable die recess with its nose tip interposed between the respective jaw apexes. Upon descent of the punch, the initially rounded pawl nose 23 will be reshaped by a combined upsetting and squeezing action that imparts a sharpened detent edge 26 extending transversely between the respective side faces of the finished pawl without need of any toe grinding operation.

Said jaws at the same time serve in the capacity of a double acting cold chisel or cutter that snips off a small surplus tip or other appended fin portion of the pawl, denoted as 28 in Fig. 3 which might otherwise jut beyond the toe edge 26. The cited pointing process serves to form a relatively long and sharply coined toe edge on a rapid productive scale and one that may be struck up reasonably smooth in a cold rather than a hot state so as to admirably fit my pawl for its intended purposes. While said dies are adapted to complete the described formations in a single operation, the same results may be had by a series of separately performed steps.

It is believed the present teachings have been sufficiently disclosed to make apparent the inherent advantages thereof to those skilled in this art. As will be obvious, such pawl improvements also find far wider application than to brake lever uses and that various changes in the structural details of my product or the manipulation

thereof may be resorted to in likewise carrying out the method herein disclosed, all without departing from the spirit and scope of my invention heretofore described and more particularly pointed out in the appended claims.

I claim:

1. The method of producing a stamped article from sheet metal stock and reshaping the edges thereof, and which method consists in stamping up a blank from said stock of which the sheared perimeter includes an initially blunt nose region; then by a coining step flattening opposite perimetric edge regions of such nose to initiate a wedge shaped toe having a jutting tip appendage, and finally by a continuation of said coining step, snipping to sever said appendage and thereby leaving a smoothly finished wedge shaped toe that is rendered sharp at the severed extremity thereof.

2. The method of producing a stamped article from sheet metal stock and reshaping the edges thereof, and which method consists in stamping up a blank from said stock of which the sheared perimeter includes an initially blunt nose region, then by a coining step flattening opposite perimetric edge regions of such nose to initiate a wedge shaped toe having a jutting tip appendage, and finally by a continuation of said coining step, snipping to sever said appendage and which snipping is performed coincident with the completion of the sharpened wedge shaped toe.

3. The method of producing a stamped article from sheet metal stock and reshaping the edges thereof, and which method consists in piercing said stock to shape up a blank whose sheared perimeter includes an initially blunt nose region and the tip portion of which nose is reduced in thickness with respect to that of the original stock, then by a coining step restoring said reduced thickness by squeezing inwardly opposite perimetric edge portions of said nose region and thereby initiate a wedge shaped toe having a jutting tip appendage, and finally by a continuation of said coining step severing said appendage to leave a smoothly finished wedge shaped toe of which the flattened faces intersect to constitute a sharp edge.

4. The method of fabricating pawl means on a rapid productive basis and which method consists in shaping up a substantially flat metal blank whose perimeter includes an initially blunt nose region and which blank is pierced with an aperture through the respective sides thereof, and thereupon by a combined coining and snipping step first flattening opposite perimetric edge portions of such nose to form a wedge shaped toe having a jutting tip appendage and finally coincident with the completion of said toe, snipping to sever said appendage and thereby leaving a smoothly finished wedge shape of which the faces intersect in a sharp edge extending transversely of the aforesaid sides.
